CAN OPENER

Joseph H. Solomon, Columbia, Pa.

Application November 30, 1945, Serial No. 631,919

3 Claims. (Cl. 30—16)

1

This invention relates to combination tools adapted for household use.

An important feature of the invention resides in the provision of a tool combining in a unitary structure a can opener, a tack puller, a hammer, a bottle uncapper, a knife sharpener and scissors grinder, a hone, a screw-driver, and a clamp for securing the tool to a fixed support when the knife sharpener and scissors grinder is to be used.

Another object of my invention is to provide a can opener of the sweep type comprising a hook adapted to penetrate a metal can top and provide a pivotal connection of the can opener with the can and a blade adjustable to different distances from the hook to accommodate the can opener to different size cans, an important feature of my invention being the provision of means for moving the cutting blade to retracted out-of-the-way position when the can opener is not in use.

A further object of my invention is to provide in a can opener of the above character, means for maintaining the cutting blade in extended operative position.

Other objects and advantages will be apparent from the following detailed description of a preferred embodiment of my invention, reference being had to the annexed drawing, in which:

Figure 1 is a perspective view of a combination tool;

Figure 2 is a detailed view of one end of the tool showing the manner in which it may be clamped to a fixed support;

Figure 3 is a fragmentary view of a can opener which constitutes one of the elements of the tool;

Figure 4 is a detailed view of the cutting blade of the can opener;

Figure 5 is a cross-sectional view of the blade taken on the line 5—5 of Fig. 4;

Figure 6 is a transverse cross-sectional view through the can opener showing the cutting blade in retracted position;

Figure 7 is a view similar to Fig. 6 but showing the blade in projected position; and

Figure 8 is a view of a modified form of the invention incorporating a can opener and bottle uncapper.

Referring to the drawing, in Fig. 1 is shown a combination tool comprising a handle member H formed with two parallel arms 1 projecting longitudinally outward from one end and having a pin 2 extending between the arms. Upon this pin is rotatably mounted a pair of circular abrasive stones 3 having opposed beveled faces biased

2

together by spring pressure and together presenting a V-slot for the reception of a knife or scissors blade.

For securing the tool to the edge of a table or other stationary support in order that the stones may be conveniently used in sharpening knives or scissors, the opposite end of the handle is formed with a pair of spaced-apart walls 4 and 5. Threadedly passing through the end wall 4 is a stud bolt 6, the inner end—that is, the end located between the walls 4 and 5—of which bears against a pressure plate 7 and the outer end of which is provided with a finger-piece 8 to facilitate turning the bolt. The pressure plate is formed with an extension 1a disposed at right-angles to the plate and passed through a guide opening 1b in the wall 4, whereby the plate is maintained in slidably assembly with the handle. As best indicated in Fig. 2, by turning the finger-piece 8 the stud bolt may be turned inwardly with the inner end of the bolt bearing against the pressure plate 7 until the latter comes to rest against a face of the support S (which may be the edge of a table top), after which further turning of the bolt causes the support to be firmly clamped between the pressure plate 7 and wall 5.

One of the arms 1 is extended outwardly beyond the abrasive stones 3 and terminates in a screw-driver 1a.

30 The finger-plate 8 is formed with a claw 9 having a V-shaped throat for the removal of nails and tacks from woodwork and the like.

A section of the handle bridges the walls 4 and 5 and lies in a plane parallel to the axis of the abrasive stones 3, and upon the outer face of this section adjacent its end remote from the abrasive stones is provided a hammer head comprising an upstanding projection 10 having a flat impact surface.

40 Intermediate the knife sharpener and the hammer head and located in the same plane with latter is a bottle uncapper formed by recessing a portion of the handle so as to define a seat 11 for the capped end of a bottle and an overhanging finger 11a for engaging under the edge of the cap for prying it loose from the bottle neck.

A hone 22 composed of some suitable material, such as leather, stone or rubber, is secured to the outer face of one of the arms 1, and is adapted for sharpening razor blades, etc.

50 Extending along the outer face of the other of the arms 1 of the tool is a can-opener, best illustrated in Figs. 3 through 7. The can opener comprises a section of sheet metal folded lengthwise so as to provide a top plate 12 and a bottom

plate 12a arranged in slightly spaced-apart parallel relation with an uninterrupted opening 13 extending along one edge thereof. The top plate 12, which lies against the outer face of the arm 1 and is secured thereto in any suitable manner, as by soldering or welding, is provided at suitably spaced distances apart with a series of transverse parallel recesses 14. The bottom plate is cut away so as to form a longitudinally extending slot 15 of substantial width terminating adjacent opposite ends of the plate and underlying the series of transverse recesses 14. Also formed in the bottom plate and lying parallel to slot 15 is another slot 16, this slot being co-extensive in length but narrower in width than the slot 15. The two plates are held in assembly by tongues 17 projecting from the ends of the bottom plate and folded under the ends of the top plate and these tongues may be suitably secured to the top plate to maintain the plates in spaced relation.

Extending into the space between the top and bottom plates 12 and 12a and spanning the slots 14 and 15 in a direction at right angles thereto, is a key 18. This key at one end is fashioned to form a finger grip 18a and a short distance inwardly thereof is bent in the shape of a flat hump 18b. Adjacent the opposite end of the key from the finger grip is affixed a cutting blade 19 pointed at its lower end, as indicated at 19a, so as to penetrate a metal can top, and sharpened along one vertical curved edge to effect the severance of the can top. The cutting blade is of a width so as to project freely outwardly through the slot 15 in the bottom plate so that by moving the key back and forth along the opening 13 the blade is likewise moved along its slot 15. The upper end of the blade is rolled into the form of a sleeve 19a which encircles the key and is secured thereto by soldering or welding; and the sleeve on its circumference diametrically opposite the blade portion is formed with a rib 20 (see Figs. 4 and 5) disposed parallel to the axis of the key and of such dimensions as to seat within a recess 14 when the key is aligned with one of said recesses. The hump 18b on the key 18 is disposed approximately at right angles to the plane of the blade, as best indicated in Fig. 4, and overlies the slot 16, so that when the cutting blade is in inoperative position and lies retracted within the slot 15, the hump occupies a position projecting into the slot 16. The slot 16 thus serves as a guideway for the key when the blade is shifted to different positions of adjustment. When the key is turned to swing the blade outwardly through its slot 15 with the rib 20 fitting into one of the recesses 14, the hump is retracted from the slot 16 and by abutting the top plate 12 acts as a stop to locate the blade in proper upright cutting position.

At the end of the tool handle opposite that which carries the abrasive wheels 3 is provided an offset pointed hook 21 adapted to be forced through the top of a metal can and serve as a pivot about which the can opener is swung in severing the top from the can. In order to facilitate severance of the metal, the blade 19 is preferably toed in slightly in a direction toward the center of its path of travel, as indicated in Fig. 5.

The cutting blade 19 normally lies retracted within the slot 15. When a can is to be opened, the hook 21 will be punched through the top of the can at approximately its center and then, by means of the key 18, the blade will be slid

lengthwise of the handle, the hump 18b riding in the slot 16, to determine the radius of the cut. With the blade aligned with one of the recesses 14, the key will be turned to swing the blade outwardly, at the same time urging the rib 20 into the recess. By moving the handle about the pivotal connection with the can top provided by the hook, the cutting blade severs the can top in a circular path forming an opening through which the contents of the can may be removed.

The combination tool just described fills a very useful purpose in performing various household jobs, such as sharpening knives and grinding scissors, honing razor blades and the like, driving or pulling tacks or nails, uncapping bottles, driving screws, or opening cans. A hole 23 in the handle allows the tool to be hung up on a nail or hook when it is not in use.

A modified form of tool is shown in Fig. 8. This device comprises a handle H¹ one end being fashioned to provide a hand grip 30 provided at its extremity with a bottle uncapper 31 corresponding in all essential respects to the bottle uncapper 11 of the form of the tool illustrated in Fig. 1.

The other end of the handle supports a can opener 32 including a cutting blade 33 and can top penetrating hook 34. The blade is mounted for adjustment lengthwise of the handle and is swingable from retracted to projected positions by means of a key 35 in the same manner as has previously been described with reference to the tool of Fig. 1.

While a preferred specific embodiment of the invention is hereinbefore set forth, it is to be understood that the invention is not limited to the exact constructions illustrated and described, but that various modifications of these details may be made within the purview of the appended claims.

I claim:

1. A can opener comprising a top plate and a bottom plate arranged in superposed spaced-apart relation and providing an opening extending along one side thereof communicating with the space between the plates, said bottom plate having an elongated slot therein, a rotatable key spanning the slot and having a finger-piece projecting outwardly through the opening, a blade secured to the key and adapted to lie within the slot in one angular position of the key and to project outwardly through the slot in another angular position of the key, and a can top penetrating hook located adjacent an end of said plates.

2. A can opener comprising a top plate and a bottom plate arranged in superposed spaced-apart relation and providing an elongated opening extending along one side thereof communicating with the space between the plates, said bottom plate having an elongated slot therein, a rotatable key spanning the slot and having a finger-piece projecting outwardly through the opening, a blade secured to the key and adapted to lie within the slot in one angular position of the key and to project outwardly through the slot in another angular position of the key, interengaging means between the key and one of said plates for guiding the key during shifting movement lengthwise of the opening and a can top penetrating hook located adjacent an end of said plates.

3. A can opener comprising a top plate and a bottom plate arranged in superposed spaced-apart relation and providing an elongated open-

ing extending along one side thereof communicating with the space between the plates, said bottom plate having an elongated slot therein, a rotatable key spanning the slot and having a finger-piece projecting outwardly through the opening, a blade secured to the key and adapted to lie within the slot in one angular position of the key and to project outwardly through the slot in another angular position of the key, a series of transverse recesses formed in the top plate, a rib upon the key adapted to seat within one of said recesses when the key is turned to blade-projecting position, a guideway in said bottom plate extending parallel to said slot, a projection upon the key adapted to extend within the guide-

way when the key is turned to blade-retracting position and to abut the top plate when the key is turned to blade-projecting position, and a can top penetrating hook located adjacent an end of said plates.
